Primary Examiner—James Gandy*Assistant Examiner*—Cathron B. Matta*Attorney, Agent, or Firm*—Melvin I. Stoltz**[57] CLAIM**

The ornamental design for a removable paint can insert, as shown and described.

DESCRIPTION

FIG. 1 is a top plan view of the removable paint can insert showing my new design;

FIG. 2 is a front elevational view thereof;

FIG. 3 is a side elevational view looking from the left side of FIG. 2, the opposite side being a mirror image thereof;

FIG. 4 is a bottom plan view thereof; and,

FIG. 5 is a rear elevational view thereof.
